VENTILATOR

Charles Davies, New York, N. Y.

Application April 15, 1932, Serial No. 605,374

12 Claims. (Cl. 98—94)

This invention relates to ventilators of the type adapted to be mounted in the window of a room; and including provisions for producing a flow of pure filtered air adequate to the purpose intended.

5 Such a ventilator comprises generically a case containing an air filter, a motor-driven air impeller to produce a current of air through the filter, and the various ducts necessary to direct the flow of air. The operation of such a ventilator, as heretofore constructed, is accompanied by a considerable amount of hum and other noise; which, as may be readily understood, constitutes a serious objection for many people and for many purposes against this type of ventilator.

15 The main object of my invention, therefore, is to provide a ventilator of this general type, capable of providing a sufficient volume of pure, filtered air and yet substantially noiseless. While the exact manner in which the noises arise is still 20 rather obscure, experience has shown that such noises are developed and transmitted both directly and meditately in the air currents produced by the air pump or blower and the reactions of the said currents with the walls of the impeller casing 25 and the ducts associated therewith. I have discovered that such noises are almost completely suppressed by embedding, forming or cutting the impeller scroll or casing and the exit air ducts in a body of sound absorbing material of substantial 30 thickness. The main feature of my invention, therefore, consists in forming the scroll of the air impeller and the associated delivery duct as a continuous passageway in a block of sound absorbing material.

35 Another important feature of my invention is a simple and efficient method of mounting and interrelating the rotor or impeller of the air pump and the sound absorbing block so as to provide for a quick and accurate assembly of the air impeller in relation to the scroll and duct.

40 A further feature of my invention is the provision of a separate air ingress chamber wherein the filter is mounted to permit quick and ready access for removal and replacement without disturbing the air pump assembly. At the same time the assembly of the entire ventilator is simplified and facilitated.

45 These and other and further objects, features, and advantages of my invention will appear in 50 more detail in the description hereinafter, in connection with the drawing, of a preferred embodiment of my invention.

In the drawing:

55 Fig. 1 is a plan view of my ventilator, the cover being removed.

Fig. 2 is a rear elevation of my ventilator.

Figs. 3 and 4 are sectional views taken along the lines 3—3 and 4—4 respectively of Fig. 2 looking in the direction of the arrows.

5 My ventilator comprises a rectangular case which may conveniently be made of wood or metal; and is provided with an imperforate bottom 1 and a removable cover 2 at the top. The front wall 3 is provided at the bottom with an air intake opening 4, which as shown may be protected by louvres. The rear wall 5 is provided at its upper portion with an air exit opening 6, also protected by louvres. Interiorly the case is divided into two compartments or chambers by the horizontal partition and mounting plate 7 10 which may conveniently be supported on and secured to flanges 8 on the interior of the case.

15 The lower compartment 9, communicating with the air intake opening 4, comprises the air intake chamber and contains the air filter which may 20 be mounted across it. The air filter comprises an open, double frame 10, hinged at one end as at 11, and resting in an inclined position on ledges 12, 13 on the front and rear walls of the case and on side ledges (not shown). The ledge 12 is positioned on the wall 3 above the opening 4 and supports the hinged end of the frame. The ledge 13 is located on the wall 5 near the bottom and supports the separable end of the frame. A corrugated filter insert having a flat edge adapted to 25 be held between the frame members is positioned in the frame. The filter insert 14 is similar in construction to the one shown in my co-pending application for Filters, Ser. No. 577,177 filed Nov. 25, 1931, now Patent No. 1,890,499, patented Dec. 35 13, 1932. A door 15 permits access to frame 10; and, when closed, abuts the end of the frame and aids in holding it in position. A flange 16 on the inside of the door presses against the upper member of frame 10 and in co-operation with ledge 40 13 holds the frame securely closed.

45 The mounting plate 7 has an upward, hollow, frusto-conical projection 17 which provides a passageway leading out of the filter chamber 9. An electric motor 18 is mounted in the passageway by means of the webs 19 secured to the inner wall of the projection 17. The motor carries on its shaft and operates the rotor or impeller 20 of a centrifugal air pump, the rotor being located just above the free edge 50 of the duct 17 and in position to receive its air supply from the latter. The upper compartment of the case is occupied by the block 21 which fits over and around the impeller 20 and the conical duct 17. The block 21 is made of 55

sound absorbing material, numerous varieties of which are now available. The block is formed with a hollow shaped to co-operate with the rotor 20 and provide therefor an air collecting scroll and a delivery duct 23. The block 21 rests upon or is secured to the flat part of the plate 7, the scroll portion 22 at its lower end surrounding the air supply duct 17, and at its upper end surrounding the impeller 20. 5 The duct 23 follows a twisted or recurved path from the outlet of the scroll 22 to the ultimate air outlet 6. The scroll portion 22 and the duct 23 have been shown in the drawing as extending from top to bottom of the block; but 10 it is clear that this is a matter of convenience in construction only. The passageway 22, 23 may be enclosed above and below in an obvious manner. The block itself and the passageway 22, 23 may be constructed by pouring or molding 15 appropriate material with good results. I have, however, found it simpler and more convenient to build the block of lamina 24 which may be cut in advance and piled flat one upon the other. The pile may then be securely tied 20 together by one or more bolts 25. If desired one or more imperforate lamina may be added at the top of the pile; and the lower laminae may be continuous except for the perforation necessary to accommodate the duct 17. I have, 25 however, found the simpler construction shown in the drawing sufficient for most purposes. The laminae themselves are of a cellular, wood-like composition material having good sound absorbing characteristics; but of course my invention is not limited to the specific material, 30 the sole requirement being that the material have good sound absorbing or insulating qualities.

The block 21, as a whole, fits over and around 40 the rotor 20 of the air pump and is mounted substantially independently of the same. It may be said that the air pump comprises the rotor 20 and the stator parts 17 and 22, the intake duct 17 being formed as a part of the 45 plate 7 and the collecting scroll 23 as part of the block 21. It will be noted that the mass of sound absorbing material 21 rests upon the plate 7 and surrounds the duct 17 and acts to damp out and prevent the transmission of sound 50 from vibrations developed in plate 7 and duct 17 by imperfections in the rotating parts. Noises due to and carried by the air currents themselves are effectually absorbed and suppressed by the walls of the scroll 22 and the long duct 23.

The operation of my ventilator is apparent 60 from the foregoing description. Under the action of the pump impeller 20 air from the exterior enters chamber 9 through opening 4, passes through filter 14 into duct 17. Thence it is delivered, by way of collecting scroll 22, to the delivery duct 23 which delivers it to the room to be ventilated by way of the opening 6. The noises incidental to the operation of the 65 pump are absorbed and suppressed by the walls of the scroll 22 and duct 23 and the mass of the block 21. The filter 14 is located in a separate chamber 9 and may be removed and replaced without disturbing the rest of the structure. To do so, the door 15 is opened or removed and the frame 10 withdrawn thru the opening. The filter insert may then be taken 70 out of the frame and a fresh one inserted. Of course it is not necessary to remove the frame itself; and, if desired, the latter may be fixedly

secured to the ledges 12 and 13, only the upper member of the frame being movable.

In compliance with the statute, I have described hereinabove a preferred embodiment of my invention; but it is to be understood that 5 numerous modifications in detail may be made therein without departing from the spirit and scope of my invention. What I claim as my invention is:

1. In a ventilator, a plate formed with a projecting air duct, an air impeller mounted to the wall of said duct in position to draw air therefrom, a block fitting over the impeller and supported by the plate and provided with a channel constituting a collecting scroll and delivery duct for the impeller. 10

2. In a ventilator, a plate formed with a projecting air duct, an air impeller mounted to the wall of said duct in position to draw air therefrom, a block of sound absorbing material supported on the plate and fitting over the impeller and provided with a channel constituting a collecting scroll and delivery duct for the impeller. 20

3. In a ventilator, a plate formed with a projecting air duct, an air impeller mounted to the wall of said duct in position to draw air therefrom, a block fitting over the impeller and supported by the plate, said block comprising a series of superposed laminae cut to provide in 30 cooperation a channel constituting a scroll and delivery duct for the impeller. 25

4. In a ventilator, a plate formed with a projecting air duct, an air impeller mounted to the wall of said duct in position to draw air therefrom, a block fitting over the impeller and supported by the plate, said block comprising a series of superposed laminae of sound absorbing material cut to provide in co-operation a channel constituting a collecting scroll and air 40 delivery duct for the impeller. 35

5. In a ventilator a case having an air intake chamber, an air filter across the intake chamber, a plate constituting one wall of the intake chamber and formed with a duct leading from the said 45 chamber, an air impeller mounted at the outlet of the said duct, a block supported by the plate and fitting over the impeller and providing in its body an air collecting scroll and delivery tube for the impeller. 50

6. In a ventilator, a case having an air intake chamber, an air filter across the intake chamber, a plate constituting one wall of the intake chamber and formed with a duct leading from the said 55 chamber, an air impeller mounted at the outlet of the said duct, a block of sound absorbing material supported by the plate and fitting over the impeller and providing in its body an air collecting scroll and delivery duct for the impeller. 60

7. In a ventilator, a case having an air intake chamber, an air filter across the intake chamber, a plate constituting one wall of the intake chamber and formed with a duct leading from the said 65 chamber, an air impeller mounted at the outlet of the said duct, a block supported by the plate and fitting over the impeller, said block comprising a series of superposed laminae cut to provide in co-operation a channel constituting an air collecting scroll and delivery duct for the 70 impeller. 70

8. In a ventilator, a case having an air intake chamber, an air filter across the intake chamber, a plate constituting one wall of the intake chamber and formed with a duct leading from the said 75

chamber, an air impeller mounted at the outlet of the said duct, a block supported by the plate and fitting over the impeller, said block comprising a series of superposed laminae of sound absorbing material cut to provide in co-operation a channel constituting an air collecting scroll and a delivery duct for the impeller.

9. In a ventilator, a case provided with an air intake chamber, a filter across the said chamber, 10 said filter comprising an open, jointed frame holding a filter body, and a door in one wall of the case permitting inspection and replacement of the filter body, and means on the door to hold together the members of the frame when the 15 said door is closed.

10. In a ventilator, a case provided with an air intake chamber, an air filter mounted across the said chamber, said filter comprising a jointed, 20 open frame holding a filter insert, a door in one wall of the case having provisions to hold together the members of the frame when the said door is closed, a plate constituting another wall of the said chamber and formed with a duct leading from said chamber, and an air impeller 25 mounted at the outlet of said duct.

11. A ventilator comprising a case, a partition

across the case dividing the latter into a filtering chamber and a pump chamber, said partition being provided with means communicating the two chambers, an air filter across the filtering chamber, an impeller in the pump chamber 5 to pass air through the aforementioned communicating means, and a block supported by the partition and fitting over the said impeller and formed with passageways co-operating with the said impeller and constituting a duct for the 10 passage of air moved by the impeller.

12. A ventilator comprising a case, a partition across the case dividing the latter into a filter chamber and a pump chamber, said partition being provided with means communicating the two 15 chambers, an air filter across the filter chamber, an impeller mounted in the pump chamber to pass air through the aforesaid means, and a block of sound absorbing material supported by the partition and fitting over the said impeller, the 20 said block being formed with a channel surrounding the impeller and leading away therefrom, the said channel providing a duct through which air is moved by the impeller.
